D. P. Miller Inventor

By *Cadmore & Co.* Attorney

UNITED STATES PATENT OFFICE.

DAVID PORTER MILLER, OF MIDDLETOWN, PENNSYLVANIA.

WRENCH.

Application filed August 21, 1922. Serial No. 583,240.

To all whom it may concern:

Be it known that I, DAVID P. MILLER, a citizen of the United States, residing at Middletown, in the county of Dauphin and State 5 of Pennsylvania, have invented a new and useful Wrench, of which the following is a specification.

This invention relates to wrenches and more particularly to pipe wrenches.

10 The object of the invention is to provide a wrench of this character which is simple in construction, cheap to manufacture and which will reliably grip and easily release.

With the foregoing and other objects in view, which will appear as the description proceeds, the invention resides in the combination and arrangement of parts and in the details of construction hereinafter described and claimed, it being understood that, within 15 the scope of what is claimed, changes in the precise embodiment of the invention shown can be made without departing from the spirit of the invention.

In the accompanying drawings:

20 Figure 1 represents a side elevation, partly in longitudinal section, of a wrench constructed in accordance with this invention, parts being broken out for convenience in illustration;

25 Fig. 2 is a rear edge view thereof; and Fig. 3 is a transverse section taken on the line 3—3 of Fig. 1.

In the embodiment illustrated, the wrench constituting this invention comprises a main body member 1 having a longitudinally extending handle 2 at one end and a laterally extending fixed jaw 3 at its other end. This jaw 3 has biting teeth 4 on its gripping face to cooperate with similar teeth on the laterally extending gripping member 7 of the movable jaw 6.

30 The main body 1 of this wrench has a recess 5 opening through the rear edge thereof and through its jaw-carrying end in which is mounted to slide the movable jaw 6 as is shown clearly in Fig. 1.

The movable jaw 6 is made substantially L-shaped and has a longitudinally extending opening 9 in the long arm thereof which 35 arm slides in the pocket or recess 5. The outer wall of the opening 9 has a series of teeth 8 which are designed to engage a soft steel cross bar 10 which extends through the opening 9 and limits the sliding movement of the jaw 6 as well as assists in holding it 40 in gripping position by its engagement with

the teeth 8. This bar 10 is shrunk in jaw 3.

The outer rear edge of the long arm of the jaw 6 is also toothed as shown at 8^a with which are engaged teeth 14 carried by a curved gripping finger 13 which is mounted on a spring shank 11 the opposite end of said shank being offset inwardly as shown at 12 and riveted to the main body 1.

45 In the use of this wrench the movable jaw 6 may be moved toward or away from the fixed jaw 3 by releasing the gripping finger 13 from its engagement with the teeth 8^a, and after said jaw has been properly positioned for use in connection with the pipe to be handled the finger 13 is again engaged with the teeth 8^a and the resiliency of the spring shank 11 operates to force the movable jaw 6 into gripping engagement with the pipe P. This forward movement of jaw 6 causes teeth 8 therefrom to biting engage the soft steel cross bar 10 which assists in holding the jaw in operative position. This cross bar 10 forms a pivot for the movable jaw 6 and being substantially rectangular in 50 form when the jaw is moved forwardly the opposed walls of the opening 9 will be engaged by the opposite ends of the cross bar which will lock the jaw in adjusted position.

55 To release jaw 6 the spring finger 13 is moved laterally away from said jaw a sufficient distance to disengage its teeth from the jaw teeth 8^a. The spring shank 11 is made of strong strain-resistant metal so that it will have sufficient strength to retain the 60 movable jaw in operative engagement with the pipe P.

65 The jaw 6 being mounted in the pocket 5 of the main body 1 is braced laterally by the side walls of said pocket and prevented from side wise movement but yet permits it to be moved freely longitudinally to adjust the gripping member 7 toward and away from jaw 3.

70 From the above description it will be seen that this improved wrench is composed of a minimum number of parts, three only being provided in addition to the rivet which secures the spring finger in position.

75 I claim:

80 In a pipe wrench a main body having a laterally extending fixed jaw and a longitudinally extending pocket opening through one end, a movable jaw mounted to slide in said pocket and having a longitudinally extending opening with teeth on one wall thereof, a cross bar extending through said 85

opening and adapted to be engaged by said teeth when the movable jaw is in operative position, the outer face of said movable jaw being toothed and a toothed spring finger carried by said body and engaged with the teeth on the rear face of said movable jaw.

In testimony that I claim the foregoing as

my own, I have hereto affixed my signature in the presence of two witnesses.

DAVID PORTER MILLER.
